(57) CLAIM

I claim the ornamental design for a head gear with projecting indicia, as shown and described.

DESCRIPTION

FIG. 1 is a left side view of a head gear with projecting indicia showing my new design: the right side being a mirror image.

FIG. 2 is an enlarged front view thereof;

FIG. 3 is a top view thereof; and,

FIG. 4 is a fragmentary perspective view thereof.

The bottom view is not visible during normal use and has been omitted.

The bottom view is not visible during normal use and has been omitted:

The broken lines shown herein are for illustrative purposes and form no part of the claimed design.
